UNITED STATES PATENT OFFICE.

PERCY H. THOMAS, OF UPPER MONTCLAIR, NEW JERSEY, ASSIGNEE TO GUGGENHEIM BROTHERS, OF NEW YORK, N. Y., A COPARTNERSHIP.

EXCAVATOR SHOVEL.

Application filed September 8, 1922, Serial No. 586,808. Renewed June 19, 1925.

To all whom it may concern:

Be it known that I, PERCY H. THOMAS, a citizen of the United States, residing at Upper Montclair, in the county of Essex, State of New Jersey, have invented certain new and useful Improvements in Excavator Shovels; and I do hereby declare the following to be a full, clear, and exact description of the invention, such as will enable others skilled in the art to which it appertains to make and use the same.

This invention relates to excavating shovels and, more particularly, to power operated shovels used largely in open diggings, and also in mines and in sub-aqueous work. The invention has for its object the provision of an improved excavating shovel.

Such excavators of the prior art comprise a turntable resting upon a suitable body structure, a boom mounted upon this turntable, a dipper stick carried by the boom and a dipper that is rigidly secured to the end of the boom. The dipper is manipulated in three movements, reciprocating relatively to the boom, hoisting, and swinging. The reciprocating movement relative to the boom is accomplished by means of a pinion driven by a shipper shaft which is carried by the boom, this pinion cooperating with a rack on the dipper stick. The hoisting is accomplished by the cooperative action of the rack and pinion and a hoisting cable attached to the dipper, or to the dipper stick, near its outer end, which passes over a sheave carried on the upper end of the boom. The swinging movement of the dipper is effected by applying a turning moment to the turntable in any convenient manner.

It is of great importance for the efficient operation of an excavator to increase the ratio of the actual digging time to the time required for the complete digging cycle. In most excavators of the prior art all three of the above mentioned movements are essential elements of the normal digging cycle. The dipper is forced, in the outward part of its reciprocating movement, into the ground by means of the rack and pinion, and, by these elements, is held against the ground or bank to be removed, while the hoisting cable moves it upwardly to fill the dipper. When the dipper is filled it is

swung around, by the rotation of the turntable, to a discharge position over the receiving vehicle which is usually on the same or a parallel track with the shovel. The dipper then has to be swung back, reciprocated inwardly and lowered before it is ready to commence another digging stroke. The angle of this swing not infrequently amounts to as much as 120° , in which case the time consumed by the swinging around is from 40 to 50% of the time required for the total digging cycle.

In the remaining prior art excavators the swinging movement has been eliminated, or partially eliminated, at the expense of increasing the hoisting element of the cycle. In this type of excavator the load of the dipper is discharged into a hopper located at the center of the excavator which delivers it to the receiving vehicle, either directly, or by means of a conveyor belt. However, these excavators, in order to deposit the dipper load in the hopper, raise it until the material will slide by gravity through a chute connecting the dipper with the hopper. This requires not only considerable time, which is roughly equal to the swinging time of the previously mentioned type of excavator, but also requires considerable power. An idea of the amount of power consumed can be had when it is considered that the dipper, of the larger sizes of excavators, holds approximately 20 cubic yards of material, which weighs some 35 tons, and which must be hoisted to a height of about 80 feet above the level of the dump car. Moreover, the descent of this load, along a steep chute from a height of 80 feet may cause damage to the excavator and the receiving vehicle, as well as wear of the chute.

According to my present invention the necessity for either hoisting, in order to cause the dipper load to slide down a chute, or swinging, is eliminated by so constructing the excavator as to carry the loaded dipper in a substantially straight path from the point of completion of the digging stroke to the discharging position, and after discharging the load to return the dipper in a substantially straight path to a position where it is again ready to immediately commence another digging stroke. This can-

- not be accomplished practically by an ordinary power shovel, inasmuch as the dipper is rigidly attached to the dipper stick, and consequently, the range of movement of the dipper without spilling its contents, is limited. The dipper of my improved shovel, however, may be actuated in a single vertical plane through all the movements of a complete digging cycle.
- 10 This is accomplished, in my improved excavator, first, by discharging the loaded dipper at a central point relative to the digging circle; second, by providing means for actuating the dipper so as to move it in a substantially straight path from the point of completion of the digging stroke to the central discharge position, and third, by so constructing the actuating devices of the dipper that they will maintain it in a sufficiently upright position substantially to prevent spilling, even though the dipper be moved up close to the base of the boom in order to reach the discharge position.
- The dipper may discharge directly into a receiver located centrally with respect to the digging circle of the excavator, such, for example, as a car or motor truck placed directly in front of the boom adjacent the side of the excavator body, but preferably the excavator itself is provided with a discharge hopper or opening through which the excavated material passes to the receiving vehicle beneath. This hopper or discharge opening is located in the vicinity of the base of the boom and preferably directly in front of it. The mechanism for actuating the dipper is so constructed that the dipper stick may be swung into a substantially vertical position, or even through the vertical so that its lower end points in the opposite direction to that assumed during the digging stroke, in order to bring the dipper over the hopper or discharge opening. Means are provided to automatically move the dipper angularly with respect to the dipper stick, during this movement, to maintain the dipper in an upright position as it is moved toward the hopper so as substantially to prevent spilling of its contents.
- 50 The hopper is preferably carried by the turntable rather than by the body of the excavator. This reduces the size and weight of the hopper because it need not be symmetrical in shape since, when so mounted, the hopper rotates with the shovel which, therefore, always discharges at about the same place in the hopper.
- It is also advantageous to mount the boom at a point a distance back from the front of the turntable rather than attaching it at, or close to, the front of the turntable as is customary in excavators previously constructed. By this arrangement the stresses in the excavator structure are materially reduced, and it is, therefore, possible to in-

crease the capacity of the dipper approximately 50% without increasing the racking stresses, or over-turning moment in the structure of the excavator.

These and other features of the invention will be better understood by reference to the following description considered in connection with the accompanying drawings. In these drawings,

Fig. 1 is a view partly in elevation and partly in section showing an excavator constructed in accordance with the preferred form of my invention;

Fig. 2 is an enlarged view of the end of the dipper stick, with the dipper attached, illustrating in detail the preferred mechanism for pivotally attaching the dipper to the dipper stick.

Fig. 3 is an enlarged view of a portion of the boom and dipper stick showing the mechanism for reciprocating the dipper stick, and for moving the auxiliary dipper stick relative to the main dipper stick for the purpose of rotating the dipper about its pivot to maintain it in an upright position;

Figs. 4 and 5 are views showing an excavating machine of modified construction;

Fig. 6 is a view partly in elevation and partly in section of an excavator somewhat similar to the type shown in Fig. 1, but adapted to make an extra wide through cut;

Figs. 7 and 8 illustrate another modification of the means for controlling the rotation of the dipper about its pivot.

Referring now to these drawings, the excavator is adapted to travel upon a four-rail track 10, and a second track 11 is provided for the receiving car 12. Both of these tracks may be of any desired gauge. The trucks 13 are of the 4 wheel type, and there are provided four of these trucks upon which the body 14 of the excavator is supported. This body is built up of suitable steel shapes and plates to furnish the required strength, and is connected with the trucks 13 by means of the raised pillars 15 which elevate the body of the excavator sufficiently to allow the receiving vehicle 12 (which may be a standard railroad car) to pass freely thereunder. On the upward part of the body 14 there is provided a circular track 16 upon which the turntable 17 is supported by means of the double flanged rollers 18. These double flanged rollers are equally spaced around the entire length of the circular track 16 to allow the turntable 17 to be easily rotated. This turntable is also constructed of steel sections suitably proportioned to carry the weight of the operating parts of the excavator, and to withstand the racking stresses which are caused by the operation of the dipper.

Resting upon the turntable 17 is the cab 19 which contains the hoisting apparatus for the dipper, and in which there is pro-

vided a suitable space for the operator, from which he has a clear view of the workings in order to properly manipulate the dipper. Mounted upon the turntable 17 is also the boom 20 which is supported in the usual manner by means of the cable 22, cooperating with the A frame 23, and the brace 24. Since an end view only of the A frame 23 is shown, only one of the two legs thereof which go down to the sides of the turntable 17 can be seen.

Carried by the boom 20, at about the center thereof, is the dipper stick 24 which is slidably connected to the boom by means 15 of triangular plates 25, which are pivoted to the shipper shaft 26, carried in suitable bearings upon the steel frame work 27 which is mounted upon the boom. Rigidly attached to the shipper shaft 26 is the pinion 28 which cooperates with the teeth of a rack 21 (Fig. 3) carried on the underside of the dipper stick 24. An electric or other motor 29 drives the shipper shaft 26 through suitable gearing and thereby reciprocates 25 the dipper stick with respect to the boom to operate the dipper as will be hereafter described. The triangular plates 25, one of which is on each side of the dipper stick, are provided with rollers 30 which cooperate with the upper surface of the dipper stick to keep the rack in mesh with the pinion 28.

The dipper 33 is pivoted at 32 on the end of the dipper stick 24. The dipper is held 35 in the proper angular position by means of the links 34, pivoted one on each side of the dipper at 35, and to the bell cranks 36 at 37. A bell crank is provided on each side of the dipper stick and these bell cranks 40 are pivotally attached to the dipper stick at 37.

Each link 34 and bell crank 36, together, form a toggle joint which is so arranged that the toggle is approximately "set" in 45 the digging positions of the dipper, but, when the dipper is moved to the dumping or discharge position the toggle is "broken." Carried on each side of the dipper stick 24 and near the lower edge thereof, are two 50 auxiliary dipper sticks 38, which are connected respectively to the bell cranks 36 at 39. These auxiliary dipper sticks 38 extend to the rear end of the main dipper stick 24, and they are also provided, on their lower surfaces, with racks 40 (Fig. 3) similar 55 to the rack on the main dipper stick. The teeth of the racks 40 are engaged by auxiliary pinions 42 rigidly mounted on the shipper shaft 36. Suitable rollers 31 are also 60 provided to maintain the engagement between the teeth of these racks and the pinions 42.

The pinions 42 are of larger diameter than the pinion 28 so that, when the shipper shaft 26 is driven by the motor 29, to

cause the dipper 33 to be moved closer to or further away from the boom, the auxiliary dipper sticks 38 are moved slightly faster and slightly further than the main dipper stick 24. In other words the auxiliary dipper sticks are moved a certain amount longitudinally with respect to the main dipper stick 24, and this motion is conveyed to the dipper 33 through the bell cranks 36 and links 34, to rotate the dipper 75 about the pivot 32. By means of this mechanism, as is shown to better advantage in Fig. 2, the dipper 33 is maintained in substantially the same angular position with respect to the dipper stick 24, as long as the dipper stick is extended from the boom, that is, toward the outer end of its stroke. However, when the dipper is drawn in toward the boom, the angular position of the dipper with respect to the dipper stick is changed 80 sufficiently so that when the boom is moved, even to a vertical position, the contents of the dipper are prevented from spilling.

Attached to the dipper 33 by means of a bail 43 is the hoisting cable 44 which passes 90 over the sheave 45, located at the outer end of the boom 20, thence to the hoisting drum 46 located in the cab 19. The control of the dipper 33 during its actual digging cycle is accomplished by means of the combined operation of the hoisting cable 44 and the dipper stick 24 as is well understood.

The excavator is provided with a discharge opening or hopper 47, which is mounted upon the turntable 17, at the foot 100 of the boom, and preferably centrally with respect to the circular track 16. This discharge hopper therefore rotates with the turntable and boom, but is always in a position to discharge into the receiving vehicle 105 12 regardless of the angular position of the turntable.

With an excavator constructed in this manner a complete digging cycle can be 110 accomplished as follows: Assuming that the dipper is in the position shown at A, Fig. 1, it is forced into the ground by means of the motor 29 acting through the main rack and pinion upon the dipper stick 24 and then moved outwardly by the combined action of the dipper stick 24 and hoisting cable 44. The dipper then proceeds further outward and upward, describing a more or less arcuate path, and is hoisted until the dipper is filled with the earth, or other material to be removed.

The dipper may not be completely filled until it reaches a relatively high position, as indicated at B, but ordinarily it will become filled at some position intermediate between A and B. Regardless, however, of the position at which the digging stroke is completed, it is desired to discharge the contents of the dipper so as to commence 125 another digging stroke, and by means of the 130

improved mechanism the dipper may be moved in a substantially direct path to the discharge position C, directly over the central discharge hopper 47. By proper manipulation of the hoisting cable, and the dipper stick motor 29, the dipper 33 is carried in a substantially straight line from the point where the digging stroke is completed to the discharge position C, and by means of the improved mechanism above described, the dipper is maintained in an upright position so as to prevent the spilling of the contents of the dipper until the dipper reaches the discharge position.

When the dipper is over the hopper 47, the contents are discharged in the ordinary manner by releasing the pivoted bottom 48 of the dipper (Fig. 5). As soon as the contents of the dipper are discharged the dipper is allowed to drop over the side of the turntable 17 under the control of the dipper stick and hoisting cable, and returned to the initial position A in a substantially direct path, to commence another digging stroke. There is no swinging movement of the dipper, or of the turntable, as an element of the normal digging cycle. Neither is there any unnecessary hoisting as an element of the normal digging cycle, because, as soon as the dipper has been hoisted just sufficiently to fill the dipper, it is carried in a substantially straight line from that spot to the discharge position, and does not have to be hoisted in order to cause the material to slide down a chute.

The only swinging of the turntable that is necessary is that required to shift the dipper through a relatively few degrees when it is desired to dig in a different vertical plane. The mechanism for causing this turning of the turntable has not been illustrated or described as it is of known construction.

Referring now to Figs. 4 and 5, there is here shown an excavator, the operation of which is very similar to that of the excavator previously described, the difference being in the mechanism for connecting the auxiliary dipper sticks 38 with the dipper in order to actuate the same about the pivot 32. In both cases toggle joints are used but while in Figs. 1 and 2 the auxiliary dipper stick is connected to the bell crank, one part of which forms one-half of the toggle; in Figs. 4 and 5 the auxiliary dipper stick is connected directly to the middle of the toggle. The toggle system of Figs. 4 and 5 comprises a pair of links 49 one on each side of the dipper stick which operate in conjunction with another similarly disposed pair of links 50. The links 49 are pivoted on the bracket 51 which is secured to the main dipper stick 24. The links 50 are pivotally attached to the dipper 33 at 52 and jointed with the links 49 at 53. The

auxiliary dipper sticks 38 are respectively attached to the common joints 53. The motion of the auxiliary dipper sticks 38 relative to the main dipper stick 24 causes the straightening out or collapsing of the toggle links 49 and 50, depending upon the direction of the motion of the auxiliary dipper sticks. Because of the choice of the relative location of the pivots 41 and 52, the angular movement of the dipper, when the dipper stick is in the outward, or digging position, is relatively small. Thus, the dipper is maintained in the proper angular position relative to the main dipper stick during the time that it is in engagement with the bank or material to be excavated. However, when the dipper has been filled it can be moved directly to the discharge position C, which is similar to that shown in Fig. 1, and during this movement the dipper is maintained in an upright position to prevent the spilling of its contents, although the dipper sticks 24 and 38 are moved to approximately the vertical position. The operation of the excavator shown in Figs. 4 and 5, is, therefore, substantially the same as that of the excavator shown in Figs. 1 and 2.

Referring to Fig. 6, there is here illustrated an excavating machine which is capable of making a wider through cut than the machines previously described. That is, this excavator possesses a larger digging radius than those heretofore mentioned. In this excavator the boom is mounted upon the turntable at a point nearer the front edge thereof than in the excavators shown in Figs. 1-5, inclusive, and in order to transfer the material from the dipper 33 to the discharge hopper 47, this hopper is provided with a hinged platform 55 which is movable in the vertical direction. This hinged platform is pivoted at 56 to the edge of the hopper 47, and extends outwardly in front of the turntable 17. Pivotally attached to the boom at 57 are one or more air cylinders 58, each having a piston rod 59 which is attached by means of the spring 60 to the platform 55 at the point 62. By means of this air cylinder 58, the hinged platform 55 may be raised to cause the material previously discharged thereon from the dipper 33, to slide forward into the hopper 47, and thence into the receiving vehicle 12. The operation of the dipper 33 is exactly the same as previously described, except that instead of discharging directly into the hopper 47, it discharges onto the hinged platform 55. The shock caused by the fall of the material from the dipper to the platform may be absorbed by means of the spring 60, and a certain amount of air which is left in the bottom of the air cylinder 58 for this purpose. The air cylinder 58 is under the control of the operator in the cab 19, and

he may easily regulate the lifting of the platform 55 so as not to interfere with the normal operation of the dipper 33 as previously described. In other words, the addition of the hinged platform does not, in any manner, lengthen the time of the digging cycle. If it is desired, instead of placing the control of the air cylinder 58 in the hands of the operator, this air cylinder may 10 be caused to be automatically controlled.

In any of the types of excavators described above, it may be found desirable, in order to move the dipper 33 to the proper discharge position over the hopper 47, to 15 move the dipper stick 24 through the vertical position, to a position where the dipper 33 will be at the left (as viewed in the drawings) of the center of suspension of the dipper stick on the boom. That is, it may be 20 found desirable to locate the hopper behind the gravity position of the dipper stick. Under these circumstances the dipper is out of control of the hoisting cable 44 and some means must be provided to move the 25 dipper to such position. Inasmuch as the dipper and dipper stick together form a compound pendulum, it will not require a very large force to overcome the unbalanced weight of the dipper, and this force is easily 30 applied by means of the arrangement of cable and weight shown in Fig. 6, in which the dipper stick is shown in the position in question. In this figure, the cable 63 is fastened to the end of the dipper stick 24 at 64, and 35 runs over the sheave 65 which is mounted near the end of the boom 20. Passing over this sheave the cable continues in a direction substantially parallel to the boom and is connected at 66 to the weight 67. This 40 weight is provided with rollers so that it may slide with ease upon suitable ways provided on the boom, and is so proportioned that it will swing the dipper and dipper stick to the desired discharge position. 45 When, however, the dipper is moved into the digging position the weight 67 will simply move along the ways, and will not interfere with the proper manipulation of the dipper.

50 Although I have shown one specific means for causing the motion of the auxiliary dipper sticks 38 with respect to the main dipper stick 24, this movement may be accomplished in a number of different 55 ways without departing from the spirit and scope of my invention.

In Figs. 7 and 8 a modification of the toggle mechanism for supporting and controlling the pivotal movement of the dipper 60 is illustrated. In this modification the dipper is caused to rotate about its pivot on the dipper stick under the influence of gravity or inertia, the movement being controlled by coacting stops operating in conjunction with the toggle system.

In this modification the dipper 33 is pivoted to the end of the dipper stick 24 at 32, as above described. The toggle mechanism comprises a link 34 connected to the dipper at 35 and to a sector 68 at the point 69. 70 Sector 68 being hinged to the dipper stick at 70 forms the second lever of the toggle joint. The circular edge of sector 68 is provided with end stops or notches 71 and 72, as well as with the intermediate stops 75 or notches 73. Control lever 74 is pivoted on the dipper stick at 75 and is biased to the position shown in Fig. 7 by means of spring 76. The short end of lever 74 is formed into a hook 77 adapted to coact with 80 the stops or notches 71, 72, and 73 to form a mechanical latch which firmly locks the toggle mechanism in any of these positions which may be required. A pair of sectors 85 68 pivoted at opposite sides of the dipper stick and a pair of cooperating links 34 are required, but only one set has been shown in the drawings for the sake of clearness.

In order to understand the operation of the apparatus of this modification, let us 90 assume that the dipper is in the position, A of Fig. 1, in which it is just commencing a digging stroke. The dipper is being hauled up by means of the hoisting cable 44. The toggle mechanism is in the position shown 95 in Fig. 7 and the mechanical latch prevents the "breaking" of the toggle so that the dipper thus held in the excavating position may be hoisted up to fill the dipper and reach the position B of Fig. 1. It is now 100 desired to transfer the dipper and its contents to the dumping position C and in order to do this without spilling the contents of the dipper it must be rotated about the pivot 32. This is accomplished either while 105 the dipper is in position B, or as it is being lowered toward position C, by pulling upon the rope 78 attached to the end of lever 74 which disengages hook 77 from notch 71. Inasmuch as the dipper and dipper stick 110 are supported entirely by cable 44 this disengagement of the latch will allow the weight of the dipper stick and dipper to cause the "breaking" of the toggle mechanism, the sector 68 rotating about pivot 70 to 115 the position shown in Fig. 8 where the hook 77 will slip behind stop 72 and lock the dipper in this position. The movement of the dipper to the dumping position C may then be continued without danger of spill. 120 The provision of intermediate notches 73 is to allow the rotation of the dipper about pivot 70 to take place in steps if desired, or to allow of variation of the digging angle of the dipper with respect to the ground.

125 After the contents of the dipper have been discharged into the hopper, cable 44 may be slackened and the dipper will then be supported by the dipper stick entirely so that the forces in the toggle mechanism will 130

be in exactly the opposite direction to the forces existing in this mechanism when the dipper was supported by the cable, as for example, in position B. On this account if 5 the mechanical latch be released by pulling on rope 78 the weight of dipper 33 will cause it to fall about pivot 32 and return sector 68 and link 34 from the position shown in Fig. 8 to the original position as 10 shown in Fig. 7, and the dipper is again ready to commence another digging stroke. By constructing an excavating machine in the manner described above, all unnecessary 15 movements of the dipper are eliminated from the normal digging cycle. It is unnecessary to swing the dipper through a horizontal angle in order to discharge its contents into the receiving vehicle, and it is also unnecessary to hoist the dipper, together 20 with its load, to a height which is sufficient to cause the load to slide down an inclined chute. Instead of these unnecessary movements the dipper is moved in practically a straight line from the point of completion 25 of the digging stroke to the discharge position. When digging in a bank of usual height, the power necessary for this transportation of material will be furnished in large measure at least, by the material itself, while descending with the dipper toward 30 the place of discharge. As soon as the material is discharged the dipper is moved in substantially a straight line to the point of commencement of the next digging stroke. Furthermore, it is unnecessary to provide a 35 special type of dipper since the standard type is readily adaptable for use. Neither is it necessary to increase the number of men required to operate the shovel, as the controls of all the various mechanisms are arranged within the reach of, and are within the capacity of a single operator. It should also be noted that certain characteristics of the power shovels, or excavators, which are 40 in use at present, are maintained, for example, the turntable feature which enables 45 the shovel to dig in any vertical plane.

I claim:

1. In an excavator, a dipper, a dipper stick, means for movably mounting the dipper on the dipper stick, and means for controlling the relative motion of the dipper and the dipper stick.
2. In an excavator, a dipper, a dipper stick, means for movably mounting the dipper on the dipper stick, and means including a toggle joint for controlling the relative motion of the dipper on the dipper stick.
3. In an excavator, a dipper, a dipper stick, means for movably mounting the dipper on the dipper stick, and means for controlling the relative motion of the dipper and the dipper stick, said means including a toggle joint adapted to be approximately 60 set in the digging position of the dipper, and

adapted to be broken in the dumping position thereof.

4. In an excavator, a dipper, a dipper stick, means for movably mounting the dipper on the dipper stick, and means for controlling the relative motion of the dipper and the dipper stick, said control means including a toggle joint adapted to be approximately set to take the digging stresses of the dipper, and a bell crank lever controlling said toggle, said lever being controlled automatically by the motion of the dipper stick.

5. In an excavator, a dipper, a dipper stick, means for movably mounting the dipper on the dipper stick, and means for controlling the relative motion of the dipper and the dipper stick, said means including a toggle joint and means automatically controlled for breaking the toggle.

6. In an excavator, a receiver for excavated material located centrally of the digging range of the excavator, a dipper stick carrying a dipper at its end, a boom on which the dipper stick is mounted at a level above that of the receiver for the excavated material, and means for actuating the dipper substantially in a vertical plane through a complete digging cycle to gather up and deliver excavated material to the receiver.

7. In an excavator, a dipper stick carrying a dipper at its end, a boom on which the dipper stick is mounted at a point substantially vertically above the discharge position of the dipper, and means for actuating the dipper substantially in a vertical plane through a complete digging cycle.

8. In an excavator, a dipper stick carrying a dipper at its end, a hopper for receiving the excavated material, a boom on which the dipper stick is mounted at a point substantially vertically above the hopper, means for actuating the dipper substantially in a vertical plane to fill the dipper with excavated material and to transfer said material to the hopper.

9. In an excavator, a dipper stick carrying a dipper at its end, a boom on which the dipper stick is mounted at a point substantially vertically above the discharge position of the dipper, means for actuating the dipper substantially in a vertical plane through a complete digging cycle, and means for maintaining the dipper in a substantially upright position during its movement from the point of completion of the digging stroke to the discharge position.

10. In an excavator, a dipper, means for actuating said dipper through a complete digging cycle, and means for maintaining said dipper in a substantially upright position during the portion of said digging cycle in which the dipper carries excavated material.

11. An excavator comprising, a body, a

digging dipper, means for forcing the dipper outwardly from the excavator body to gather up material to be excavated and for moving the thus filled dipper in a substantially straight path from the point of completion of the digging stroke to the discharge position.

12. An excavator comprising, a body, a digging dipper, means for forcing the dipper outwardly from the excavator body to gather up material to be excavated and for moving the thus filled dipper in a substantially straight path from the point of completion of the digging stroke to the discharge position, and means for maintaining the dipper in a substantially upright position during said movement.

13. An excavator comprising a body, a boom, a dipper, a dipper stick, means for moving the dipper in a substantially straight path from the point of completion of the digging stroke to the discharge position, and automatic means for maintaining the dipper in a substantially upright position during said movement.

14. An excavator having a dipper and a centrally located discharge opening, and provided with means for moving the dipper into discharge position relative to said opening, and means for maintaining the dipper in a substantially upright position while it is moved to the discharge position.

15. In an excavator, a body, a boom, a central discharge hopper, a dipper stick carried by the boom, a dipper attached to the dipper stick and manipulated by connections with the boom to move outwardly from the excavator body to gather up material to be excavated and to move inwardly to discharge its load into the said hopper.

16. An excavator comprising, a body, a boom mounted thereon, a central discharge hopper, a dipper stick carried by the boom, a dipper supported by the dipper stick, means for moving the dipper outwardly from the excavator body to gather up material to be excavated and inwardly to discharge said material into said hopper and means for maintaining the dipper in a substantially upright position as it is moved to said discharge position.

17. In an excavator, a body, a boom mounted thereon, a dipper stick carried by the boom, a dipper supported by the dipper stick, means for moving the dipper outwardly to gather up material to be excavated and inwardly so as to discharge said material into a centrally located receiver, and means for maintaining the dipper in a substantially upright position to prevent the spilling of its contents as the dipper is moved from the point of completion of the digging stroke to the centrally located discharge position.

18. An excavator comprising, a body, a boom mounted thereon, a central discharge hopper, a dipper stick operably carried on the boom, a dipper movably mounted on the dipper stick, and means for moving the dipper relative to the dipper stick to prevent the spilling of its contents as the dipper is moved to the discharge position.

19. An excavator comprising, a body, a boom, a main dipper stick operably mounted on the boom, a dipper movably mounted on said dipper stick, an auxiliary dipper stick carried by the main dipper stick for varying the position of the dipper relative to the main dipper stick, and means for actuating both dipper sticks.

20. An excavator comprising, a body, a boom, a main dipper stick operably mounted on the boom, a dipper movably mounted on said dipper stick, an auxiliary dipper stick carried by the main dipper stick for varying the position of the dipper relative to the main dipper stick and means for simultaneously actuating both dipper sticks.

21. An excavator comprising, a body, a boom, a main dipper stick operably mounted on the boom, a dipper pivoted on said dipper stick, an auxiliary dipper stick carried by the main dipper stick and adapted to vary the angular position of the dipper, means for operating the main dipper stick and means for moving the auxiliary dipper stick relatively to the main dipper stick.

22. An excavator comprising, a boom, a main dipper stick, a dipper pivoted to the main dipper stick and an auxiliary dipper stick automatically actuated to rotate the dipper about its pivot as the dipper is moved toward the boom.

23. An excavator comprising a body, a boom, a main dipper stick, a dipper pivoted to the main dipper stick, an auxiliary dipper stick connected to the dipper through a bell crank and lever, said auxiliary dipper stick being automatically actuated to rotate the dipper about its pivot as the dipper is moved toward the boom.

24. An excavator comprising a body, a boom, a dipper stick, a dipper pivoted to the main dipper stick, an auxiliary dipper stick connected to the dipper through a toggle mechanism, said auxiliary dipper stick being automatically actuated to rotate the dipper about its pivot as the dipper is moved toward the boom.

25. An excavator comprising a body, a boom, a main dipper stick, a dipper pivoted thereto, an auxiliary dipper stick adjacent said main dipper stick adapted by longitudinal movement to rotate the dipper about its pivot, and automatic means for moving the said auxiliary dipper stick relative to the main dipper stick as the dipper is drawn toward the boom.

26. An excavator comprising, a body, a boom, a main dipper stick operably mounted on the boom, a dipper pivoted on said dipper stick, an auxiliary dipper stick adjacent to the main dipper stick and adapted to vary the angular position of the dipper, a shipper shaft mounted on the boom, pinions on said shaft engaging racks on the respective handles, the pinion operating the auxiliary dipper stick being of larger diameter than the pinion operating the main dipper stick.
27. An excavator comprising, a body, a boom, a centrally located discharge opening, a main dipper stick operably mounted on the boom, a dipper pivoted on said dipper stick, an auxiliary dipper stick carried by the main dipper stick and connected to the dipper by means of a bell crank mechanism, means for operating the main dipper stick to move the dipper to discharge position over the centrally located opening, and means for simultaneously moving the auxiliary dipper stick relatively to the main dipper stick.
28. An excavator comprising a body, a boom, a main dipper stick, a dipper pivoted thereto, an auxiliary dipper stick adjacent said main dipper stick and adapted by longitudinal movement to rotate the dipper about its pivot, a shipper shaft carried on the boom equipped with pinions engaging racks on the main and auxiliary dipper stick, the pinion for actuating the auxiliary dipper stick being of larger diameter than the pinion actuating the main dipper stick.
29. An excavator comprising, a body, a turntable carrying a boom, a hopper carried by the turntable in front of the boom, a main dipper stick directly connected to the dipper, an auxiliary dipper stick connected to the dipper by a bell-crank mechanism mounted on the main dipper stick, means for hoisting the dipper and means for simultaneously reciprocating the dipper sticks and for moving the auxiliary dipper stick relative to the main dipper stick, whereby the dipper is operated to dig and to discharge its load into the hopper.
30. In an excavating machine, a body, a boom, a turntable having a central discharge opening with a movable dumping platform cooperating therewith, a dipper mounted upon a dipper stick carried by the boom, connections between the boom and the dipper for manipulating the dipper to discharge its load upon the dumping platform, and means for raising said platform so as to discharge the load through the central opening.
31. In an excavating machine, a body, a boom, a turntable having a central discharge opening with a movable dumping platform cooperating therewith, a dipper stick car-
- ried by the boom, a dipper attached to the dipper stick and manipulated by connections with the boom to discharge its load upon the dumping platform, means for relieving the shock of discharge to said platform and means for causing said platform to discharge into said central opening.
32. In an excavating machine, a body, a boom, a turntable having a central discharge opening with a movable dumping platform cooperating therewith, a dipper stick carried by the boom, a dipper attached to the dipper stick and manipulated by connections with the boom to discharge its load upon the dumping platform, pneumatic means for relieving the shock of discharge to said platform and pneumatic means for causing said platform to discharge into said central opening.
33. In an excavator, a dipper stick, a dipper, a central hopper located behind the gravity position of the dipper stick, means for moving the dipper from the excavating position to the dumping position, including positive means for moving the dipper stick beyond its gravity position.
34. In an excavator, a dipper stick, a dipper, a central hopper located behind the gravity position of the dipper stick, means for moving the dipper from the excavating position to the dumping position, said means including a rope secured to the upper portion of the dipper stick and running over a fixed pulley and a weight attached to said rope.
35. In an excavator, a boom, a dipper stick, a dipper, a central hopper located behind the gravity position of the dipper stick, means for moving the dipper from the excavating position to the dumping position, said means including a rope connected to the upper portion of the dipper stick and running over a pulley on the boom, and a weight slideable on said boom and attached to said rope.
36. An excavator comprising, a body, a boom, a main dipper stick, a dipper pivoted to the main dipper stick, and an auxiliary dipper stick automatically actuated to rotate the dipper about its pivot as the dipper is moved away from the boom.
37. An excavator comprising, a body, a boom, a main dipper stick, a dipper pivoted to the main dipper stick, an auxiliary dipper stick connected to the dipper through a bell crank lever, said auxiliary dipper stick being automatically actuated to rotate the dipper about its pivot as the dipper is moved away from the boom.
38. An excavator comprising, a body, a boom, a dipper stick, a dipper pivoted to the main dipper stick, an auxiliary dipper stick connected to the dipper through a toggle mechanism, said auxiliary dipper

stick being automatically actuated to rotate the dipper about its pivot as the dipper is moved away from the boom.

39. An excavator comprising, a body, a boom, a main dipper stick, a dipper pivoted thereto, an auxiliary dipper stick adjacent said main dipper stick adapted by longi-

tudinal movement to rotate the dipper about its pivot, and automatic means for moving the auxiliary dipper stick relative to the main dipper stick as the dipper is moved away from the boom. 10

In testimony whereof I affix my signature.

PERCY H. THOMAS.
